MACHINE FOR GRINDING THREADS

Fernand Turrettini, Bellevue-Geneva, Switzerland, assignor to the firm Societe Genevoise d'Instruments de Physique, Geneva, Switzerland, a firm of Switzerland

Application March 28, 1941, Serial No. 385,761
In Switzerland May 15, 1940

5 Claims. (Cl. 51—95)

The present invention relates to a thread grinding machine having a truing device for the grinding wheel, which device is mounted on the table carrying the work piece.

It is an object of the invention to provide a machine of the above kind having a truing device which operates in a position which is in exact relation to the grinding wheel in order that the profile of the latter may be engendered always in the same position.

Another object of the invention is to provide means which permit of bringing the truing device instantaneously into the exact working position.

The machine according to the invention is characterized by two stops carried by the machine frame and cooperating one with an abutment carried by the table and the other with an abutment carried by the nut of the guide screw, which nut is mounted on the table in such a manner that it can slide in the latter without turning with the screw, the machine comprises also a device exerting a horizontal traction upon the table, and a hand control lever which permits of changing the direction of said traction so as to apply either the abutment of the nut against the corresponding stop on the frame, position in which the work piece can be ground, or the abutment of the table against the corresponding stop on the frame, position in which the grinding wheel can be trued.

The annexed drawing represents, by way of example, one embodiment of the present invention.

Fig. 1 is a transverse section. The Figures 2 and 3 show two different views of a detail.

In the figures, 1 designates the grinding wheel carried by a special support 1_a, and 9 is the table of the machine, adapted to slide on the frame 19 of said machine. Said table which is intended to carry the work piece, the thread of which is to be rectified, presents for this purpose a spindle 2, capable of turning in the head stock 2_a, and a back centre 3 between which is disposed said piece to which the spindle 2 imparts a rotatory movement. 4 is the truing device of the grinding wheel 1 placed in advance of the table 9. 5 is the driving pinion of the spindle, 6 is the head carrying the reduction gears the composition of which determines the pitch of the thread to be rectified, 7 is the driving pinion of the guide screw 10 which is maintained rotatably without axial play in a bearing 8 integral with the table 9.

The guide screw 10 has its threaded part 11 55

engaged in a tubular nut 12 which is axially movable in a bore 14 of the table. To this nut 12 is fixed radially a finger 15 which can slide along in a slot of a bar 16 fixed to the table 9, this finger prevents the nut from turning while leaving to it the possibility to slide longitudinally.

The nut 12 terminates in an abutment 17 which during grinding bears upon a fixed stop 18 mounted on the frame 19.

10 The table 9 carries a second abutment 20 which when the truing apparatus 4 is to be brought to the working position in front of the grinding wheel 1, has to bear upon a stop 21 also mounted on the frame 19.

15 This will be obtained by operating by means of a pinion 23 a rack 22 guided in the table 9; this pinion carried by the table is integral with an axis 24 upon which is disposed a control lever 25 which is provided with a stop button 29 adapted to render the same immovable on the table in two distinct fixed positions 30 and 31 (see Figs. 2 and 3).

20 The chain 32 of the counter-weight 33 is fastened at 26 on the rack 22; it passes between two return pulleys 27 and 28 and is rolled up in part on one or the other of said pulleys according to the relative position of the fastening point 26 with respect to the table 9.

25 From the above it is seen that the nut 12 has no rigid and permanent connection with the frame 19 and that it can be removed rapidly from the stop 18 when one wishes to pass from the grinding position to the truing position.

This is obtained by provoking by means of lever 25 passing from the position 30 to the position 31, and pinion 23 a sliding of the rack 22 carrying the fastening point 26 of the chain of the counter-weight 33 which exerts upon the table 9 a traction assuring contact between the abutment 17 and the stop 18 so long as the chain passes over the pulley 27.

30 When by the action of the lever 25 the movement of the fastening point 26 causes the chain 32 to pass from the pulley 27 to the pulley 28, the traction exerted upon the table by the counter-weight will be in the inverse direction and will move the table so as to bring the abutment 20 into contact with the stop 21. This contact will be maintained by the immobilization at 31 of the arm 25.

35 It is seen that in this machine the rapid action of a hand control lever enables to pass the table alternately from the position of grinding the work piece to the position for truing the grinding wheel; the constancy of the two positions, through

the action of abutments, ensures great precision.

From the foregoing, it is believed that the construction and advantages of the present invention may be readily understood by those skilled in the art without further description, it being borne in mind that numerous changes may be made in the details disclosed without departing from the spirit of the invention as set out in the following claims.

What is claimed and desired to be secured by Letters Patent is:

1. A machine for grinding threads including a frame, a table carrying a work piece and movable relative to the frame, a grinding wheel adjacent the table for operating on the work piece, a truing device for the grinding wheel mounted on the table, a guide screw having a threaded outer end and journaled in the table on the under side thereof, a nut threaded on the guide screw and mounted for sliding but non rational movement relative to the table, an abutment on the outer end of the nut, an abutment on the under side of the table in alignment with the abutment on the nut, two additional oppositely facing abutments mounted on the frame between the first mentioned abutments and in alignment therewith, and means for exerting a horizontal traction on the table in opposite directions so as to apply either the abutment on the nut against the corresponding abutment on the frame in which position the work piece can be ground or the abutment on the table against the corresponding abutment in which position the grinding wheel can be trued.

2. A machine for grinding threads as claimed in claim 1 in which the means for exerting the horizontal traction on the table are hand operated means and locking means are provided for locking the table in either position.

3. A machine for grinding threads as claimed in claim 1 in which the traction exerting means includes a counterweight, a flexible member having one end fixed to the counterweight, two adjacent pulleys between which passes the flexible member prior to its being rolled upon one or the other of said pulleys according to the direction of traction exerted upon the table and hand operated means including a rack adapted to slide in the table and to which is pivotally mounted the other end of the flexible member, a pinion carried by the table and engaging said rack, an

operating organ carried by the table and controlling the pinion, said organ being capable of assuming two fixed positions whereby the position of the pivot point of the rack and flexible member with respect to the pulleys is changed when the organ passes from one of its positions to the other.

4. In a machine for grinding threads comprising a frame, a work table mounted slidably on said frame, and a grinding wheel truing device mounted on said table outside of the stocks, in combination, a guide screw mounted in the table with its driving gear, a nut engaging said screw and mounted slidably in the table, said nut being provided with an axial tubular extension carrying an end abutment, a two ended stop mounted on the frame and cooperating by one end with said nut abutment and by the other end with a fixed abutment of the table, and a hand controlled horizontal traction device for quick table displacement within the limits of said abutments, from the thread grinding position to the wheel truing position and vice versa.

5. In a machine for grinding threads comprising a frame, a work table mounted slidably on said frame, and a grinding wheel truing device mounted on said table outside of the stocks, in combination, a guide screw mounted in the table with its driving gear, a nut engaging said screw and mounted slidably in the table, said nut being provided with an axial tubular extension carrying an end abutment, a two ended stop mounted on the frame and cooperating by one end with said nut abutment and by the other end with a fixed abutment of the table, and a hand controlled horizontal traction device for quick table displacement within the limits of said abutments, from the thread grinding position to the wheel truing position and vice-versa, said horizontal traction device comprising a handle mounted on the table apron, a pinion fixed on the axis of said handle, a locking device carried by this handle and cooperating with two diametrically opposed locking positions, a rack mounted slidably in the table and engaging said pinion, a flexible element, fastened by one end in a point of said rack, two adjacent pulleys mounted in the machine frame and a counterweight hung by the other end of said flexible element led down between said pulleys.

FERNAND TURRETTINI.
